UNITED STATES PATENT OFFICE.

ADNIRAM J. COOKE, OF ROCHESTER, NEW YORK.

REVERSIBLE SEAT.

SPECIFICATION forming part of Letters Patent No. 341,319, dated May 4, 1886.

Application filed September 28, 1885. Serial No. 178,412. (No model.)

To all whom it may concern:

Be it known that I, ADNIRAM J. COOKE, a citizen of the United States, and a resident of Rochester, in the county of Monroe and State 5 of New York, have invented certain new and useful Improvements in Reversible Seats; and I do hereby declare that the following is a full, clear, and exact description of the invention, which will enable others skilled in the 10 art to which it appertains to make and use the same, reference being had to the accompanying drawings, which form a part of this specification, and in which—

Figure 1 is a side view of my improved reversible seat. Fig. 2 is a similar view showing it reversed. Fig. 3 is a vertical sectional view showing the inner side of one of the end pieces of the frame and of the end of the seat. Fig. 4 is a front view of the seat; and Fig. 5 is 20 a side view of one of the sector-shaped frames J J, which will be hereinafter described.

Similar letters of reference indicate corresponding parts in all the figures.

My invention has relation to reversible seats, 25 especially intended for car-seats; and it consists in the improved construction and combination of parts of the same, as hereinafter more fully described and claimed.

In the accompanying drawings, the letters A 30 indicate the end frames of the seat, which frames are connected at their lower ends and at their middles by means of longitudinal rods B B, and at a distance from their bases by rods C C, which form foot-rests for the seats adjoining the seat.

The upper ends of the end frames are provided with the usual arm-rests, D, and the widening upper portions of the end frames are formed with segmental slots E E, having their 40 center at the middles of the upper edges of the end frames, and extending from the upper edges to near the central lines of the frames. The lower ends of these slots are formed with downwardly-projecting notches F, and are also 45 preferably formed at points above the notches F with similar notches, G, to admit of adjustment of the chair-seat, as will be hereinafter described.

The seat consists of two widely-diverging 50 V-shaped end frames or pieces, H H, which

are connected near their ends and at their apices by longitudinal rods I, and sector-shaped frames J J are secured with their segmental portions K to the middles of the outer sides of the V-shaped frames, while the radial 55 arms L L of the frames are connected at the center of the sector and formed with a V-shaped slot, M, at the said center.

Headed bolts N N project outward from the ends of the segmental portions of the sector-shaped frames and slide in the segmental slots in the end frames, and the sector-shaped frames of the swinging seat are pivoted upon bolts O, secured in the end frames at the centers of the segmental slots and passing through 60 the V-shaped slots at the centers of the sector-shaped frames.

The narrow ends or points m of the V-shaped slots M point toward the segmental portions K of the sector-shaped frames J, as 70 will be more clearly seen by reference to Fig. 5 of the drawings, and it will be seen that as the seat is swung, with its bolts sliding in the segmental slots in the end frames, when one pair of these bolts arrives at the lower end of 75 the slots at the notches, the seat may be depressed, so as to cause the bolts to enter the notches, the V-shaped slots sliding with one of their arms upon the pivotal bolts, so as to allow the seat to be depressed, the seat resting 80 upon one of two pairs of lugs, P, upon the inside of the side frames. In this manner it will be seen that what is seat when the seat is in one position will be back when the seat is reversed, and vice versa, so that 85 equal wear will be gotten out of both seat and back, and the end pieces of the seat being V-shaped, or, rather, curved, the seat portion or back may be all covered with one piece of fabric, which will save labor in upholstering 90 the seat. This shape will also add to the comfort of the person sitting in the seat, and the seat may be adjusted to different angles of inclination by adjusting the sliding bolts in the different notches.

The foot-rests may in this seat be placed 95 comparatively higher than in the usual construction of reversible car-seats, which will also add to the comfort of the person sitting in the seat, enabling him to take a comfortable 100

and easy position, the swinging curved or V-shaped seat-frame occupying less room than a stationary seat and a swinging back, and consequently allowing the foot-rest bars to be 5 placed farther up upon the end frames.

The seat may very easily be tilted, all that is necessary for tilting it being to lift the seat slightly, so as to raise the sliding bolts out of their notches, the V-shaped slots at the 10 centers of the sector-shaped frames sliding upon the pivotal bolts with one of their arms, when the seat may be easily tilted, and will, by its own weight, fall into position, with the sliding bolts resting in the notches at the ends of 15 the segmental slots.

It follows that although the seat is especially adapted for railroad-carriages, it may be used wherever a reversible seat may be desired, and it may of course likewise be of sufficient 20 width for more than two persons, or it may be only of sufficient width for one person, as the occasion may require it.

Suitable means for locking the seat in place may be provided, although it is not necessary 25 to provide any means for holding the sliding bolts in place in the notches, the weight of the seat and of the person sitting in the seat forcing the said bolts into the notches; but in

railroad-carriages or other public places it may be desirable to have locking means for 30 securing the seats in a uniform position.

I am aware that it is not new to construct reversible seats to swing upon a central pivot, so as to make the sides act alternately as back and seat, and I do not claim such construction, broadly; but 35

I claim and desire to secure by Letters Patent of the United States—

In a reversible seat, the combination, with wide - topped frames having two segmental 40 slots near their upper ends, each of said slots having a notch at its lower end, of a pin projecting through and sliding in each of said slots, a swinging seat, the ends of which are provided with a segmental sector secured thereto, 45 the pivotal point of said sectors being provided with a V-shaped slot, and a pin projecting through said slot and supporting said seat, substantially as and for the purpose set forth.

In testimony that I claim the foregoing as 50 my own I have hereunto affixed my signature in presence of two witnesses.

ADNIRAM J. COOKE.
